US00D875150S

(12) **United States Design Patent** (10) **Patent No.:** **US D875,150 S**
(45) **Date of Patent:** **** Feb. 11, 2020**

(54) **END PLATE FOR MOTION GUIDE DEVICE**

(71) Applicant: **THK CO., LTD.**, Tokyo (JP)

(72) Inventors: **Hiroyuki Kishi**, Tokyo (JP);
Mitsumasa Wada, Tokyo (JP);
Hiroyoshi Yasutake, Tokyo (JP); **Eriko Oshima**, Tokyo (JP)

(73) Assignee: **THK CO., LTD.**, Tokyo (JP)

(**) Term: **15 Years**

(21) Appl. No.: **29/627,657**

(22) Filed: **Nov. 29, 2017**

(30) **Foreign Application Priority Data**

May 31, 2017 (JP) 2017-011618
May 31, 2017 (JP) 2017-011619

OTHER PUBLICATIONS

Office Action dated Feb. 2, 2018, issued in counterpart Japanese Application No. 2017-011618.

Primary Examiner — Patricia A Palasik

(74) *Attorney, Agent, or Firm* — Westerman, Hattori, Daniels & Adrian, LLP

(57) **CLAIM**

The ornamental design for an end plate for motion guide device, as shown and described.

DESCRIPTION

FIG. 1 is a front elevational view of an end plate for motion guide device, showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a perspective view, showing the front, top, and right-side thereof.

FIG. 8 is a perspective view, showing the rear, bottom, and left-side thereof.

FIG. 9 is a perspective view, showing the front, bottom, and right-side thereof; and,

FIG. 10 is a perspective view, showing the rear, top, and left-side thereof.

The broken lines illustrate environmental structure and form no part of the claimed design. The dot-dash lines form boundaries of the claimed design and form no part thereof.

1 Claim, 10 Drawing Sheets
